METALLIC CONTAINER AND METHOD OF
MAKING THE SAME

Paul H. Meyer, Bellwood, Leo Bethke, Melrose Park, and James P. Walker, Maywood, Ill., assignors to Solar-Sturges Mfg. Co., Melrose Park, Ill., a corporation of Illinois

Application September 30, 1933, Serial No. 691,592

2 Claims. (Cl. 113—120)

The present invention has to do with a metallic container and more particularly with a metal barrel for liquor such as beer and the like.

It is an object of the present invention to construct a metallic container or barrel which may be manufactured at low cost and which will be satisfactory for the purposes intended.

Another object of the invention is to provide a metallic container for beer and the like of improved construction.

A further object of the invention is to provide a single wall metal barrel or container suitable for beer and the like, which barrel is strong and sturdily constructed to withstand the hard usage to which a beer barrel is subjected in use.

A still further object of the invention is to provide a novel bilge ring and method of constructing it.

Another and yet further object of the invention is to provide a novel method of attaching a filling bung bushing in place in a metal barrel.

A still further object of the invention is to provide a metal barrel of novel construction whereby one head or both heads may be readily removed for replacement or repair without damaging any part of the barrel.

The above, other and further objects of the invention will be apparent from the following description, accompanying drawings, and appended claims.

Generally speaking, the barrel contemplates a body portion made of a single thickness of metal constructed initially as a cylinder, the provision of a bilge ring having in it a plurality of runners or ribs which are arranged circumferentially of the ring and in which the inner surface of the ring is concave. The ring is attached to the body by expansion of the body to secure intimate fit of the body and ring. Furthermore, the invention contemplates the securing of a bung bushing in the bilge ring, and after the barrel body has been expanded to provide the bilge in it, the body of the barrel in alignment with the bung bushing is perforated, using the bung as a punch, the margin of the body defining the aperture being secured to the bung bushing.

An embodiment of the present invention is illustrated in the accompanying drawings and the views thereof are as follows:

Figure 1 is a vertical sectional view of a metal container constructed in accordance with the principles of the present invention.

Figure 2 is an enlarged fragmental portion, in section, showing the manner of sweating various

elements of the barrel together in permanent association.

Figure 3 is a fragmental sectional view showing the parts, which in Figure 2 are separated, in assembled relation.

Figure 4 is an enlarged fragmental sectional view taken substantially in the plane indicated by the line IV—IV of Figure 1.

Figure 5 is a fragmental view of a punch and die arrangement showing the manner of punching the hole in the barrel body in register with the bung bushing and illustrating certain features in section.

Figure 6 is a view similar to Figure 5 showing the manner of curling the margin of the hole in the barrel body into a recess formed in the bung bushing.

The drawings will now be explained.

The metallic container of the present invention includes a body A which is made initially as a cylinder and preferably from flat stock bent with the abutting edges welded together in any suitable manner. Near each end of the body A is formed an annular shoulder 1 which extends about the body near the ends and serves as means to limit the inward position of the head of the barrel when the same are applied.

There are two heads B and C, each of which is provided with a cylindrical flange 2 disposed to extend outwardly towards the end of the barrel or container when the heads are applied. Preferably, the heads are dished at 3 for the purpose of rigidity.

At each end of the barrel is provided an end ring designated generally at D, which ring has a flange portion 4 for bearing against the outsides of the ends of the barrel and an inturned portion 5 which lies at substantially right angles to the flange 4, and which portion 5 provides a hand hold for lifting and carrying the barrel. The portion 5 is formed by inturning a part of the material of which the ring D is made.

The entire body is tinned on both sides as at 6 and 7 after the body has been fashioned in cylindrical form. The heads and the rings D are also tinned all over the same. The bilge ring is tinned, inside and outside, after the filling bushing has been secured to the bilge ring. The head and end rings D are assembled by inserting the heads against the shoulders 1 with the flanges 2 of the heads projecting outwardly and then the rings D are applied in position as shown in Figures 1 and 3. The ends of the barrel are then subjected to a temperature which is sufficient to

melt the tin and thus the parts are sweated together in permanent association.

The installation of the heads and the rings D in the manner just described is effected after the 5 bilge ring has been applied to the barrel and the body subjected to expansion action to form the bilge in it and thus secure the bilge ring in place on the barrel.

A bilge ring, designated generally at E, is made 10 from a piece of flat stock which is curved into cylindrical form with the ends welded together in any suitable manner. The ring is then expanded to provide in it a plurality of runners or ribs, there being two such shown in the drawings. 15 There are thus formed runners F and G. Formation of the runners by expansion of the ring forms fillets 32 between the plane of the ring and the faces 10 of the runners. In order to reduce the fillets to walls which are substantially perpendicular to the plane of the body of the ring, that is to the flanges 11 and 12 of the ring, the ring is then rolled whereupon the fillets are reduced to the shape shown at 13 and 14 of the runners F and G. In this manner the walls 13 and 14 are 20 substantially perpendicular to the planes of the flanges 12 and 11 of the bilge ring and consequently substantially perpendicular to the expanded body of the barrel so that it is possible to make the bilge ring of lighter material than 25 otherwise possible where these walls are not substantially perpendicular to the surface of the barrel. The rolling of the ring, as just described, also dishes the flanges 11 and 12 of the bilge ring to provide a concave inner surface on the ring. 30 The degree of concavity of this ring when rolled is slightly greater than the finished expanded bilge of the barrel when completed. By providing the concave surface in the bilge ring, then when the barrel body is expanded, the flanges 11 35 and 12 of the ring are stretched thus increasing the holding effect between the ring and the barrel.

After the bilge ring has been fully formed, it is then subjected to tool action to press outwardly or offset a part of the cylindrical portion 45 between the ribs, as at 33 in Figure 4, to provide a seat for a filling bung bushing. The offset portion 33 is then punched, providing a bushing aperture 34.

In order to apply a filling bung bushing to the 50 barrel, a bushing H, preferably of steel, is provided. The bushing is illustrated in section in Figures 1, 4, 5 and 6, and is formed with a central opening 15 which tapers inwardly for receiving a bung or other sealing means after the barrel has 55 been filled. When the bung bushing H is formed, there is formed in it an annular recess 17 opening toward the lower side of the bushing. In the formation of the bung bushing H the edge 18 is formed as sharp as possible for the purpose of utilizing this edge as a punch for a purpose to 60 be later explained.

The bung bushing H is inserted in the aperture 34 in the bilge ring E in the space between the runners F and G from the inside of such aperture. 65 The outer portion of the bung bushing has an up-standing annular flange 19 which projects through the aperture or hole 34 in the bilge ring E with the margin of such hole surrounding the shoulder 19 at its base. The bung bushing is then 70 welded as at 20 to the bilge ring E, the welding being done against the inside of the bilge ring surrounding the bung bushing H.

After the bung bushing H has been applied to the bilge ring in the manner stated, the ring and 75 bushing are completely tinned and the bilge ring

E is then applied over the cylindrical body of the barrel A and the barrel A is then subjected to expansion action to produce the bilge in the barrel. Such expansion of the barrel body forms generally the barrel body to the concavity of the 5 bilge ring E and thus intimately connects the bilge ring to the barrel body by such expansion action.

The present invention contemplates the formation of the bung hole in the barrel body in the following manner:

After the bilge ring has been secured to the barrel body by expansion of the body, a tool, designated 21 in Figures 5 and 6 and having a reduced portion 22, is applied against the exterior of the bung bushing H with the part 22 entering the 15 aperture or opening 15 in the bushing with the shoulders 23 of the tool bearing against the outer surface of the bung bushing. The part 22 is tapered, slightly, at 24 for the purpose of centering the tool 21 in the bung bushing H. 20

A die 25 having a sharpened edge at 26 is then applied inside of the barrel body in alignment with the bung bushing H. Pressure is then applied to the part 21 and to the die 25 so that the die is pushed against the barrel body A adjacent the 25 bung bushing H. Continued movement of the die then forces the barrel body portion against the sharpened edge 18 of the bung bushing whereupon there is blanked or punched out from the barrel body, a blank 27. Movement of the die is 30 continued to force the portion indicated at 28 of the barrel body A forming the marginal portion of the hole so pierced into the recess 17 of the bung bushing. During such action the margins of such hole become distorted and crimped 35 in the recess 17, as may be observed from Figure 6. When this has been accomplished, the member 21 and die 25 are removed, and then the deformed marginal portions of the hole are welded or sweated in the recess 17 as indicated at 28 in 40 Figure 4, thereby permanently securing the bung bushing H to the barrel body A and to the bilge ring E.

In this manner there is provided an opening 45 in the barrel body in register with the filling bung bushing H, which is of proper size and which is so secured to the bung bushing as to make a leak tight joint.

After the bilge ring E has been applied in the manner just described, then the heads B 50 and C are applied to the ends of the body of the barrel and the end rings D are applied and sweated together in the manner heretofore described.

Prior to the installation of the head B, a tap 55 bush 29 is inserted in the head B and secured thereto by welding as indicated at 30. The parts are so fashioned that the bung bushing H lies within the surfaces or faces 10 of the runners F and G while the tap bush 29 is with 60 in the extremity of the end ring D at this end of the barrel.

In the rolling of the runners F and G, portions of the surfaces thereof, as for instance at 31, are preferably flattened to afford flattened 65 surfaces for rolling the barrel.

It will be observed from Figure 1 that the bilge ring E extends over the major portion of the body of the barrel when the structure is completed. The bilge ring so applied reinforces 70 the body of the barrel and prevents damage to the barrel due to rough usage. It will be observed from Figure 1 that a very small portion of the body A of the barrel is exposed to rough treatment, as most of the surface of the barrel 75

is protected by the bilge ring E and the end rings D.

By the utilization of the bilge ring of the character herein described, a single walled barrel is provided which is strong and sturdy and which will stand the rough usage to which barrels, such for instance as beer barrels, are subjected in handling.

If perchance it should become necessary to repair or replace either of the heads of the barrel, the damaged head may be removed by subjecting that end of the barrel to sufficient heat to melt the solder whereupon the head may be removed without damage to any part of the barrel and the head so removed repaired or replaced by a new one.

The provision of the flattened surfaces 31 on the runners or ribs prevents tilting of the barrel endwise when on the runners, a feature which is desirable when the barrel is being rolled or when it is being carried in a truck or wagon or stored.

Tinning the entire body and heads of the container, as well as the bilge ring, prevents rust, and thus prolongs the usefulness of the container.

When such container is used for beer, the insides of the body and heads are covered with pitch. In the event any of the pitch should chip off, the tinned metal would prevent rust and spoilage of the beer.

Whenever the tap bush 29 is placed elsewhere than in the center of a head, then the opposite head is provided with a well for the reception of the beer pump rod.

The invention has been described herein more or less precisely as to details, yet it is to be understood that the invention is not to be limited

thereby, as changes may be made in the arrangement and proportion of parts, and equivalents may be substituted without departing from the spirit and scope of the invention.

The invention is claimed as follows:

1. A metallic barrel comprising a first elongated cylinder provided with end closure means and having an aperture formed in a wall thereof, a second elongated cylinder enveloping a major portion of said first cylinder and being shaped to define a pair of longitudinally spaced outer bands and an intermediate band tightly fitting said first cylinder, said intermediate band having an aperture formed therein in alignment with the aperture in said first cylinder, said second cylinder also being shaped to define a pair of longitudinally spaced and longitudinally extending runners each of which is positioned between an outer band and the intermediate band and is connected thereto by transversely extending fillets, and a bung bushing connected to said first and said second cylinders and aligned with the apertures therein.

2. The method of forming a metallic barrel which comprises the steps of forming a first elongated cylinder, forming a second elongated cylinder to envelop a major portion of said first cylinder, working said second cylinder to define a pair of longitudinally spaced and longitudinally extending outer bands and an intermediate band in tight engagement with said first cylinder, and to define a pair of longitudinally spaced runners each of which is positioned between an outer band and the intermediate band and is connected thereto by transversely extending fillets.
